UNITED STATES PATENT OFFICE.

NOEL STATHAM, OF IRVINGTON, NEW YORK.

SAFETY RAZOR.

Application filed July 15, 1920. Serial No. 396,436.

To all whom it may concern:

Be it known that I, NOEL STATHAM, a subject of the King of Great Britain, and resident of Irvington, county of Westches-

ter, State of New York, have made a certain new and useful Invention Relating to Safety Razors, of which the following is a specification, taken in connection with the accompanying drawing.

10 This invention relates especially to razors which may be of the safety razor type and with which stropping devices may cooperate so that the razor blade may be stropped without disengaging it from the blade hold-

15 er and cooperating handle which support it in shaving position. The handle which preferably has a dished up or concave pivotal portion may advantageously be formed of resilient sheet metal and have its

20 lower or gripping portion shaped to be readily gripped by the operator. A hinge support having a similarly concaved pivotal portion cooperation with and preferably facing the pivotal portion of the handle,

25 may be operatively connected therewith by a fixed or adjustable pivot allowing the swinging movement of these parts. This hinge support preferably carries a hinge pin or device at some distance from the

30 pivot, so as to connect a blade holder to the support in such a way that it can fold either into angularly projecting shaving position or down into substantially the plane of the handle when desired. The

35 blade holder which may have resilient gripping fingers or portions to securely engage or hold a razor blade, is preferably of the universal type adapted to accommodate practically any standard thin safety razor

40 blade. A guard cooperating with the blade holder may advantageously be pivoted to the hinge pin and resilient or other connecting clips or devices may securely hold this guard in cooperation with the blade holder and

45 razor blade for shaving. A detacher which may be loosely pivoted or connected to the guard may have an integral detacher lever projecting for convenient engagement by the operator, so as to swing the detacher against

50 the blade holder and force it away from the guard for stropping purposes for instance. It is sometimes desirable to have the blade holder held securely in its angularly projecting shaving position and for this purpose a tightening nut or device may be ar-

55 ranged on the hinge to force these hinge

portions tightly and substantially rigidly together or in some cases definitely interlocking latched devices may be used for this purpose.

60 In the accompanying drawing showing in a somewhat diagrammatic way various illustrative embodiments of this invention,

Fig. 1 is a perspective view showing an illustrative razor in shaving position.

65 Fig. 2 is a corresponding transverse section thereof.

Fig. 3 is a side view showing the razor with the blade holder swung up into the plane of the handle.

70 Fig. 4 is a similar detail view showing the guard swung down against the handle.

Fig. 5 is an enlarged detail of the connecting clip taken substantially along the line 5-5 of Fig. 1.

75 Fig. 6 is a side view of another illustrative razor.

Fig. 7 is a transverse section thereof, taken substantially along the lines 7-7 of Fig. 6.

80 Fig. 8 is a transverse sectional view of another illustrative razor.

Fig. 8^a is an enlarged detail showing the latching devices.

85 Fig. 9 is a side view thereof showing the blade holder folded outward into substantially the plane of the handle and

Fig. 10 is a rear side view thereof.

90 In the illustrative embodiment of the invention shown in Figs. 1 to 5, the razor handle may in many cases be advantageously formed of resilient sheet metal such as brass which may be electroplated with nickel, silver, etc., if desired. This handle

1 is preferably formed with a dished or concave pivotal portion adjacent the pivot 2 which may connect thereto through the corresponding dished or concaved portion, the hinge support 3 of similar resilient sheet metal if desired. The hinge pin 23 may be

95 mounted on this hinge support in any suitable way as by bending suitable portions 4 of the hinge support around the pin, the intermediate portion of sheet metal 17 being left in extending position as indicated in Figs. 1 and 2. The blade holder 6 of

100 similar sheet metal if desired, may have one or more integral portions such as 5 bent around this hinge pin and forcibly engaging the resilient extension 17 of the support

105 in some cases, so as to frictionally hold the blade holder in any angular position in

which it may be folded. As indicated more in detail in Fig. 4, the blade holder may have the integral or other resilient gripping fingers 9, adapted to engage and grip a razor blade, the blade holder having in some cases an offset portion 7 adjacent its free edge. The blade holder is preferably of such size and shape as to accommodate substantially all of the standard safety razor blades of the thin type and the curved ends of the blade holder may be formed with locating flanges such as 26, while locating pins or projections 25 may engage and align some thicker or backed razor blades, which may be used in this holder.

The guard 11 of any suitable construction and material may in some cases be formed of resilient sheet metal having the integral hinge portions 10, extending around the hinge pin 23, while connecting clips or devices, such as the integral clips 24 may be formed on this guard to more or less embrace or snap around the edge of the blade holder as shown in Fig. 5, so as to detachably hold these parts in cooperation during shaving for example. The guard may of course be formed with a curved guiding lip 12 adjacent the edge of the razor blade and suitable cleaning slots or openings may be formed in this part of the guard. In many cases it is desirable to have a detaching device to quickly detach or disengage the guard and blade holder and as shown in Figs. 2 and 4 the detacher 14 of resilient sheet metal may have its integral detacher lever 13 extend through a slot 19 in the guard, so as to project slightly beyond the edge 12 of the guard if desired. When the parts are in the position shown in Fig. 2, forcible downward pressure on the detacher lever swings the detacher up against the blade holder or blade so as to force the same away from the guard and allow these parts to swing away from each other about the hinge pin 23. If desired this detacher lever may be formed with shoulders 18 loosely engaged by a retainer 58 which may be soldered or otherwise secured to the guard, so as to permanently connect the detacher thereto.

The guard and holder together with the razor blade may be folded or moved about the hinge pin into any desired position and may be moved upward into angularly projecting shaving position as indicated in Figs. 1 and 2. The blade holder and support may be swung about the pivot 2 into any desired angular position with respect to the handle, so that an angular or draw cut may be secured if desired. In some cases it is advantageous to form angular aligning devices or detents in the hinge support and handle and for this purpose integral stamped up projections or recesses may be employed such as 20 and 21 on the hinge support in

Fig. 3 and 22 on the cooperating handle as shown in Fig. 2. It is desirable to hold the razor in such angularly extended position as is shown in Fig. 2 and for this purpose a tightening or locking nut such as the cap 70 nut 16 may advantageously be used on the end of the hinge pin 23, the opposite end of the hinge pin being formed with a head 55 and with a fin or projection 52 engaging the part 10 if desired. By screwing up this tightening nut 16 the hinge portions of the device may be tightly forced together so as to prevent undesirable movement after the razor blade has been adjusted and the tightening nut may either be left in this position or loosened when the blade or guard are to be folded into another position.

Figs. 6 and 7 show another form of the device in which the blade holder 6 having in some cases the laterally projecting edges 28 may be formed with integral hinge portions 35 extending around the hinge pin 23 and connected to the large area resilient gripping portion 29 which may have one or more flaring inserting portions 30 adjacent to the blade edge if desired. Either part of this blade holder may be formed with integral or other blade aligners 33 in such position as to engage some of the usual holes 32 formed in the razor blades such as 31, so that the blade may be definitely held in proper position when slipped or forced into the blade holder.

As shown in Figs. 8 to 10, the blade holder 6 may in some cases be formed with definite locking depressions or notches 36 in its hinge portions 5 which may cooperate with a frictional or positive holding device as the hinge latch 37 which may be slidably or otherwise loosely mounted in the hinge support as by extending through the slots 42, 43 therein. A spring such as 39 may be connected to or extend around the pivot 2 and may engage the projection 38 on the latch, so as to normally force it into the locking depressions 36 and hold the blade holder up in its angularly projecting shaving position. By forming these locking depressions in the inclined or ratchet form shown in Fig. 8^a, the blade holder may be folded or moved upward freely, the latch snapping past these projections, while preventing retrograde movement of the blade holder. The latch may however be manually withdrawn as by pushing downward on the latch end 41 so as to release the latch and allow the blade holder to be folded down into substantially the plane of the handle. A more positive form of connecting device is shown in connection with this razor and these connecting clips 47 may as indicated in Fig. 9 be pivoted to the guard, so that when forced inward into holding position their ends or holding portions 45 lock around the blade holder, to positively hold

these parts together in operative position until the clips are swung outward, as by engagement with their projecting portions 46.

This invention has been described in connection with a number of illustrative embodiments, parts, proportions, materials, devices, arrangements and methods of manufacture and use, to the details of which disclosure the invention is not of course to be limited, since what is claimed as new and what is desired to be secured by Letters Patent is set forth in the appended claims.

1. In safety razors a handle, a hinge support pivoted to said handle, a hinge pin embraced by integral portions of said hinge support, a sheet metal blade holder having portions extending around said hinge pin and having resilient gripping portions to engage and hold a razor blade, a sheet metal guard having pivotal portions extending around said hinge pin and having resilient connecting clip devices to engage said blade holder and a tightening nut on said hinge pin to force together and releasably hold the hinge portions of said blade holder and guard and prevent undesirable angular movement thereof about said hinge pin.

2. In safety razors a handle, a hinge support pivoted to said handle, a hinge pin embraced by portions of said hinge support, a blade holder having portions extending around said hinge pin and having resilient gripping portions to engage and hold a razor blade, a guard having pivotal portions extending around said hinge pin and a tightening device to force together and releasably hold the hinge portions of said blade holder and guard.

3. In safety razors a sheet metal handle having a concave pivotal portion, a hinge support having a cooperating concave pivotal portion facing the concave pivotal portion of said handle and pivotally connected thereto, a blade holder hinged to said hinge support and having locating flanges and projections, a guard pivotally connected to said blade holder and formed with connecting clips and a loosely pivoted detacher between said guard and blade holder and having a connected detacher lever extending through said guard for operating said detacher.

4. In safety razors a sheet metal handle, a hinge support pivotally connected thereto, a blade holder hinged to said hinge support and having locating flanges and projections, and a loosely pivoted detacher between said guard and blade holder and having a connected detacher lever extending through said guard for operating said detacher.

5. In safety razors a handle having a concave pivotal portion, a gripping blade holder adjustably connected to said handle and hav-

ing locating projections, a guard pivotally connected to said blade holder and formed with resilient connecting clips and a loosely pivoted detacher between said guard and blade holder and having a connected detacher lever extending out from between said blade holder and said guard for operating said detacher.

6. In safety razors a handle, a blade holder adjustably connected to said handle, a guard pivotally connected to said blade holder and formed with resilient connecting clips and a loosely connected pivoted detacher between said guard and blade holder and having a connected detacher lever extending out from between said blade holder and said guard for operating said detacher.

7. In safety razors a sheet metal handle having a dished up concave pivotal portion and an adjacent projection, a hinge support having a cooperating concave pivotal portion facing the concave pivotal portion of said handle and pivotally connected thereto, a blade holder hinged to said hinge support and having a portion frictionally engaging said handle projection and a guard pivotally connected to said blade holder.

8. In safety razors a handle, a universal gripping blade holder adapted to receive practically any standard thin safety razor blade adjustably connected to said handle and having locating edge flanges and intermediate projections and a guard pivotally connected to said blade holder and formed with connecting clips.

9. In safety razors a handle having a connected hinge pin, a sheet metal blade holder having portions extending around said hinge pin and having resilient gripping fingers to engage and hold a razor blade and having locating portions to cooperate with and locate a razor blade with relation thereto, a sheet metal guard having portions extending around said hinge pin and a tightening device on said hinge pin to force together and releasably hold together said hinge pin and the hinge portions of said blade holder and guard and prevent undesirable angular movement thereof about said hinge pin.

10. In safety razors a handle having a connected hinge pin, a blade holder having portions extending around said hinge pin, a guard having portions extending around said hinge pin and a tightening device on said hinge pin to force together and releasably hold together said hinge pin and the hinge portions of said blade holder and guard and prevent undesirable angular movement thereof about said hinge pin.

NOEL STATHAM.
